His Attorney.

UNITED STATES PATENT OFFICE.

EUGENE D. EBY, OF PITTSFIELD, MASSACHUSETTS, ASSIGNOR TO GENERAL ELECTRIC COMPANY, A CORPORATION OF NEW YORK.

BUSHING.

Application filed May 5, 1919. Serial No. 294,831.

To all whom it may concern:

Be it known that I, EUGENE D. EBY, a citizen of the United States, residing at Pittsfield, in the county of Berkshire, State 5 of Massachusetts, have invented certain new and useful Improvements in Bushings, of which the following is a specification.

My invention relates to bushings adapted to house the leading-in connections for 10 encased electrical apparatus, and has for an object an improved construction which is durable, weather proof, and economical.

More specifically my invention relates to bushings for current transformers and current metering devices which have their windings arranged in a plurality of sections; and is designed to provide not only a safe insulating structure but to provide convenient means for changing the connections to the 20 winding sections in a safe and economical manner.

In bushings for use on current transformers in service with high potential conductors, it is necessary to insulate the incoming leads 25 from the line from ground, although little insulation is required between leads themselves in the bushing, since their relative difference of potential is small. Also where the current transformer is of standard construction it is necessary generally to provide suitable means for changing the ratio 30 of transformation. This change in the ratio of transformation is conveniently effected by changing the connections to the primary 35 which is usually made in two or more sections; such change in connections generally comprises a change from series to multiple connection or vice versa.

Heretofore it has been customary to bring 40 a plurality of leads out from the windings to the exterior of the bushing where the desired connections were made.

This practice however is accompanied by 45 the problem of making the joint in the connections proof against the weather and also proof electrically against grounds, etc. and when once made is often changed only with difficulty.

In the practice of my invention, such 50 changes may be readily effected and the connections are always protected when in service in a safe and weather-proof manner because I provide the bushing structure with a housing for the lead terminals, which is 55 an integral part of the bushing. This hous-

ing I have arranged in a novel manner to provide not only the necessary seals for the leads against moisture and weather conditions but also to provide the needed access to the leads for making the required changes 60 in the connections in a safe and convenient manner and yet afford proper insulation to all the parts.

For a more complete understanding of the nature and objects of my invention, reference should be had to the following detailed description of my invention as applied to the construction of bushings when taken in connection with the accompanying drawing in which:

Fig. 1 shows a bushing partly in elevation and partly in section constructed to embody my invention. Figs. 2 and 3 show plan views of the various electrical connections afforded by the use of my invention. Fig. 4 is a fragmentary sectional view showing certain details of my invention, and Fig. 5 shows in diagrammatic fashion the general scheme of connections for sections of a primary winding served by my 80 improved bushing.

Referring now to the drawing, and to Fig. 1 in particular, 10 denotes generally the bushing structure which comprises the insulating member 11, cemented or otherwise rigidly supported in the securing ring 12, and the metallic cap 13 likewise rigidly secured, as by cement, to the member 11. The bushing also has the interiorly pendent member comprising a metallic or conducting tube 15 encased in a substantially uniform cylindrical jacket 16 of insulating material. The pendent member is supported from the top of the bushing structure through the tube 15 which engages with 90 an interior portion of the cap 13.

Instead of directly fastening the ring 12 to the tank of the current transformer or other apparatus served by the bushing, an auxiliary ring or collar 14 is preferably 100 employed, since a wider range of adaptability is thus procured, to which collar the ring 12 is bolted or otherwise secured, the collar 14 in turn being secured to the apparatus casing (not shown).

To avoid, and hence to protect against, a difference of potential across various points on the interior of the casing in the space above the surface of the liquid cooling and insulating medium, shown at 8, I provide a 110

conducting shield 17, supported on the surface of the pendent member, the shield being constructed with rolled ends and provided with the conducting spinning 18 which 5 has a ground connection shown at 18' (see Fig. 4) made substantially as explained in U. S. Letters Patent No. 1,304,283 issued in my name May 20, 1919. The spinning 18 thus provides a convenient closure for the 10 lower end of member 11 and will also serve as a support for any insulating filling which it may be desired to place therein. To insure a weather tight joint between the ring 12 and collar 14, one or more gaskets, such 15 as shown at g and g' are inserted. Where the spinning 18 has a special grounding connection, as shown at 18', the gaskets will with advantage be made to embrace the projecting rim or collar portion of the spinning, one on each side as shown in Fig. 4.

Four leads 20 are brought out from the sections of primary winding, here shown as two in number and denoted w^1 and w^2 in Fig. 5, for the apparatus served and are 20 brought up through the tube 15 into the cap 13 and are there secured to suitable terminals a , b , c and d mounted on a terminal board 21. The leads 22 to the aerial connections pass out through suitable outlets or pockets 23 formed in the cap 13. A 25 separate pocket for each lead 22 is here shown, though obviously a single pocket would do.

To support the terminal board in place 30 and also to impose a definite potential upon the cap 13, one stud or bolt which connects a lead 20 to the terminal board is extended to engage with a boss 24 formed on the interior of the cap 13.

40 A hardened filling of insulating compound 25 is poured around the leads 20 and 22 beneath the terminal board 21 in order to securely hold them safely in place, but to prevent this compound from infiltrating between the leads into the tube 15,

45 a stop 26 is provided in the upper end of the tube 15. This stop consists of one or more discs of insulating material perforated to accommodate the four leads 20.

50 To fix this stop 26 in a definite position with respect to the leads 20, a wrapping of cord 27 or other insulating material is secured on the leads 20 which wrapping prevents the stop 26 from passing lower on the leads. The ends of the leads 20 which enter the cap 13 may be reinforced by a further wrapping of insulating material as shown at 28 and held in the desired spaced relation by an insulating plug 29.

60 The cap 13 which thus houses the terminal board 21, is closed by a suitable cover 30 secured thereto in a weather tight manner by means of bolts 31. The cover 30 is also shown as having a threaded recess 32, 65 engaged by a stud 33.

The recess 32 comprises a suitable means for attaching a protective device, such as a spark gap, in connection with the apparatus served by the bushing. When no such device is applied, the stud 33 conveniently 70 serves to keep it free from dirt and sediment that would otherwise accumulate in it.

In operation, when it is desired to connect the windings w^1 and w^2 in multiple, the cover 30 is removed and conducting 75 bars, shown at 40 and 41 in Fig. 2, are connected respectively across terminals a , b , and c , d . The current then coming in on a lead 22 to the terminal a , while traversing the winding w^1 in flowing to terminal c , thence to d and to the other lead 22, will branch from terminal a to terminal b and traverse winding w^2 in parallel with winding w^1 coming directly to the other lead 22 by way of terminal d . 80

When again it is desired to change the ratio of transformation from that given by the multiple arrangement to that given by the series arrangement, the cover 30 having been removed, the series connection is effected by connecting a conducting bar, shown at 45 in Fig. 3, across the terminals b , c . The current then coming in on one lead 22 to terminal a will traverse winding w^1 flowing to terminal c , and thence through the bar 45 to b to traverse winding w^2 (since it is now in series with winding w^1) whence it will flow to the other lead 22 by way of terminal d . 85

Having now described what is at present the best means known to me for carrying out my invention, I would have it understood that such means are merely illustrative and that I do not mean to be limited thereby to the exact details shown nor in the choice of recognized equivalents except as defined in my claims hereunto appended.

What I claim as new and desire to secure by Letters Patent of the United States, is:—

1. In a bushing structure, the combination with an upper hollow insulating member, of a hollow cap secured to said member and comprising a base portion with side outlets and a removable cover, a tubular member within said insulating member and depending from said cap, a terminal board mounted within said cap, and a plurality of leads extending through said tubular member from said terminal board. 100

2. In a bushing structure, the combination with an insulating member, of a pendent tubular member projecting from the lower end of the first said member, a main fastening ring secured to said lower end, an auxiliary ring secured to said main fastening ring, a conducting member on the projecting portion of said tubular member provided with a collar projecting between said rings, and means for making a weather 105

tight seal between said rings and said collar.

3. In a bushing structure, the combination with an insulating member, of a pendant tubular member projecting from the lower end of the first said member, a main fastening ring secured to said lower end, an auxiliary ring secured to said main fastening ring, a conducting sleeve on the projecting portion of said tubular member, a conducting spinning secured to said sleeve and having a rim projecting between said rings, means for making a weather tight seal between said rings and said rim, and a ground connection between said spinning and said auxiliary ring.
4. A bushing structure comprising upper and lower insulating members, a main fastening ring on said upper member, an auxiliary ring secured to said main ring, and a conducting member overlying a portion of the surface of said lower insulating member having a collar projecting between said rings, and weather tight packing means between said collar and said rings. 25

In witness whereof, I have hereunto set my hand this 2nd day of May 1919.

EUGENE D. EBY.
